UNITED STATES PATENT OFFICE.

EARL R. DAVIS, OF CINCINNATI, OHIO

FLYING-MACHINE.

1,113,881.

Specification of Letters Patent. Patented Oct. 13, 1914.

Application filed February 10, 1914. Serial No. 817,885.

To all whom it may concern:

Be it known that I, EARL R. DAVIS, a citizen of the United States, residing at Cincinnati, in the county of Hamilton and State of Ohio, have invented new and useful Improvements in Flying-Machines, of which the following is a specification.

This invention relates to flying machines of the aerodynamical type, and the principal object of the invention is to provide a flying machine which, without the use of balancing mechanism auxiliary to its normal working parts, will under all normal conditions, through its own inherent balancing properties, maintain its equilibrium and, in the event that it should turn over in any direction under any unusual disturbing force, as when suddenly encountering a gale, will right itself and assume a safe gliding angle for sustentation or to insure a safe descent to the ground.

A further object of the invention is to provide a machine in which the construction, relative proportions and relative arrangement of the parts, load weight and balancing factors are such as to secure the aforesaid actions, as well as to adapt the machine for flying at any proper angle of incidence without disturbing its balancing properties and whereby any tendency of the machine to lag or drop back to an unbalanced position will be prevented and the machine caused to automatically assume a gliding attitude.

A still further object of the invention is to provide a machine having the defined characteristics and which at the same time possesses speed and lifting power.

The invention consists of the features of construction, combination and arrangement of parts herein fully described and claimed reference being had to the accompanying drawings in which:

Figure 1 is a side elevation of a flying machine embodying my invention in a flying attitude. Fig. 2 is a similar view of the machine in a gliding or volplaning attitude. Fig. 3 is a similar view of the machine in its standing attitude. Fig. 4 is a front elevation of the machine. Fig. 5 is a top plan view of the machine. Fig. 6 is a vertical transverse section on line 6—6 of Fig. 5.

In the practical embodiment of my invention I provide a nacelle body 1, preferably of streamline or pisciform contour, and constituting a car or body portion proper 2 and an empennage or tail portion 3. The car or body portion 2 is provided with the usual cock pit 4, and serves as an inclosure for the aviator's seat 5, the motor 6 and the elements of the steering or controlling gear. The empennage or tail portion 3 carries at its stern end a fixed stability tail 7, a horizontal rudder or vertically adjustable tail piece 8, and a laterally swinging vertical rudder 9, which rudders are adapted to be connected with and adjusted by any suitable or preferred type of controlling device (not shown) arranged, as stated, within the car or body 2 so as to be within convenient reach of the aviator. The rudder 8 is so arranged that when disposed in a normal or neutral position it extends on a line coinciding with the longitudinal center of the nacelle.

The motor 6 drives a forward tractor propeller 10, the shaft 11 of which is disposed in a horizontal plane coinciding with the longitudinal center of the body and in longitudinal alignment with the rudder 8 when the latter is disposed in a neutral position, whereby the center of thrust of the propeller will be delivered in a line coinciding substantially with the longitudinal center of the machine when in a flying attitude, so that maximum propelling efficiency will be obtained.

The machine is provided with a supporting surface comprising a pair of laterally extending wings 12 which project equidistantly beyond opposite sides of the body 2. These wings have any suitable fore-and-aft curvature or inclination, and are preferably of rectangular or square form, in order to secure compactness of structure, minimize danger from side gusts, to permit of stronger bracing, and to obtain increased stability, on account of less side leverage than in machines of ordinary construction. The wings are at a dihedral angle, to secure inherent lateral stability, and are rigidly fastened at their inner ends to the sides of the car or body 2 adjacent to the upper surface thereof, or above the part of the car or body carrying the entire load weight,

2
by which the point of suspension of the machine when flying is placed entirely above the load weight, which gives an extremely low center of gravity. The car or body, acting in conjunction with the weight of the load carried therein, thereby serves as a pendulum operating by gravity to maintain longitudinal stability, and coacting with the dihedral wings to maintain lateral stability.

10 When the machine is in flight, and perfectly balanced, the centers of gravity and pressure coincide at the point upon the supporting surface along the line 6-6 shown in Fig. 6, and when the machine is so balanced the tail portion 3 carries no weight and the plane 8 acts solely as an elevating rudder. The car or body 1 carries suitable launching and alighting gear 13, which may include cushioning wheels, while the

15 tail 3 is provided with a depending cushioning wheel or fender 14 to support the tail when the machine is in standing attitude clear of the ground, as well as to protect the tail and rudders from injury in the

20 launching and landing actions.

It will be observed from the foregoing description that by constructing and arranging the parts of the machine as above described, automatic stability, both longitudinally and laterally, is obtainable inherently in the machine without the use of auxiliary balancing appliances of any character, and that in turning or steering the machine laterally the dihedral angle of the wings

25 effects a sufficient temporary lateral tilting of the machine out of a balanced position to properly bank the machine. It will also be observed that the wings are set high upon the body for a proper underhang of the

30 load weight below the point of suspension, and that the propeller is so arranged that its lifting thrust will be sufficient when the machine is in a flying or climbing attitude, to raise the forward end of the body so that

35 the center of weight will be thrust slightly forward of a vertical line intersecting the point of suspension, whereby in the event of the stoppage of the motor the load weight acting as a pendulum will tilt the forward

40 end of the body downward, causing the machine to automatically assume a correct gliding attitude for gravitational sustentation to set the machine incidentally for a safe descent to the ground.

45 Owing to the fact that the machine is perfectly balanced along the suspension line when it is in a normal flying attitude, and in such attitude of the machine the movable tail plane 8 is relieved of the work of sus-

50 taining the weight of the tail, it is evident that the said adjustable tail piece or elevating plane 8 may be set or adjusted to prime the machine to fly at any proper angle of incidence, without the necessity of changing

the position of the supporting surface, the 65 resistance of the load weight when the machine is traveling at an abnormal angle of incidence being balanced by the increased pressure of the air upon the tail plane, by which longitudinal balance is preserved. If, 70 at any time when the machine is in flight, the motor should suddenly stop the tendency of the body to drop slightly and to tilt forward to a balancing degree, in the manner heretofore described, obviates any liability 75 of the machine dropping back or losing its longitudinal balance in a rearward direction, absolute safety is secured by the movement of the machine to a correct gliding position owing to the fact that the machine is inherently balanced against loss of stability laterally or longitudinally, it will be apparent that if under abnormal conditions, as when encountering a sudden gale, the machine should be blown over in any direction, 80 it will within a minimum falling space right itself and assume a gliding attitude for safe 85 descent.

From the foregoing description, taken in connection with the drawings, the construction and mode of operation of my improved flying machine will be readily understood, and it will be seen that by a novel construction and arrangement of the usual parts a machine having inherent stability to an exceptional degree is produced without employing auxiliary stabilizing devices of any kind or character. Also it will be seen that the construction described provides a strong and durable machine which may be 95 designed for speed or weight carrying, without 100 sacrificing the principles of the invention.

I claim:-

A flying machine comprising a nacelle of pisciform contour, said nacelle comprising 105 a forward body portion or car and a rearwardly extending tail, a fixed tail plane at the rear of the tail of the body, a vertical rudder in proximity thereto, an elevating tail plane pivoted for vertical movement at 110 the rear edge of the fixed tail plane, said fixed tail plane being arranged in the line of the longitudinal center of the body and the movable tail plane having a neutral position coinciding with said line and being 115 adjustable above and below the same, dihedral wings projecting laterally from the car and at a point adjacent the top thereof so that the point of suspension when the machine is in flight will be wholly above 120 the longitudinal center line of the car, a motor, and means arranged within the bottom of the car to carry and arrange the load weight below the horizontal longitudinal center of the car, a propeller shaft driven 125 by the motor and arranged on a line coinciding with the horizontal longitudinal center of the car between the point of suspension

and load weight, and a propeller operated by said shaft and arranged so that the lifting portion of its thrust will elevate the forward end of the body to a degree to throw the center of weight slightly forward of the vertical line of the point of suspension when the machine is in flight.

In testimony whereof I affix my signature in presence of two witnesses.

EARL R. DAVIS.
